CLAIM

The ornamental design of a pressed metal battery terminal connector, substantially as shown and described.

DESCRIPTION

FIG. 1 is a plan view of a pressed metal battery terminal connector showing our new design;

FIG. 2 is an end view thereof;

FIG. 3 is a side view thereof;

FIG. 4 is an opposite end view thereof; and

FIG. 5 is a perspective view thereof, taken from the side opposite that shown in FIG. 3.

FIG. 2

FIG. 4

FIG. 1

FIG. 3

FIG. 5
